UNITED STATES PATENT OFFICE.

NORRIS E. NELSON AND OTTO NELSON, OF SEATTLE, WASHINGTON.

AUTOMATIC CIRCUIT BREAKER.

Application filed October 3, 1919. Serial No. 328,180.

To all whom it may concern:

Be it known that we, NORRIS E. NELSON and OTTO NELSON, citizens of the United States, residing at Seattle, in the county of King and State of Washington, have invented certain new and useful Improvements in Automatic Circuit Breakers; and we do hereby declare the following to be a full, clear, and exact description of the invention, such as will enable others skilled in the art to which it appertains to make and use the same.

This invention relates to automatic current breakers, and while particularly adapted to a current breaker having a local magnetic circuit broken by a breaking of the main circuit, it is not limited thereto.

An object of this invention is to provide a circuit breaker for use in shops and on machines and in such places as where a current of high voltage is used and it is desired to break a circuit from a remote point, or any number of points, where it is not desirable or possible to carry a high voltage current.

A further object in this invention is to provide a simplified and more efficient means to break a current from a remote point, or any number of points.

A further object of this invention is to utilize standard stock and easily purchasable elements in the construction of a device of this character.

A further object of this invention is to provide a device of this character which automatically breaks the local magnetic circuit when the main circuit is broken.

With these and other objects in view, the invention consists of the constructions combination and the detail and arrangement of parts as hereinafter more fully described and claimed.

In the drawings:

Figure 1 is a side elevation of this device.

Figure 2 is a front elevation of this device.

Figure 3 is a rear elevation of this device.

Figure 4 is a plan view.

Figure 5 is a detail partly broken away of the catch mechanism.

Figure 6 is a diagrammatic wiring plan.

In detail the invention comprises an insulated base 2 having affixed thereon clips 3, 3^a and 3^b, the said clips forming a bar

for a knife switch having knives respectively pivotally mounted on said clips at 5, 5^a and 5^b, the said knives being designated respectively 4, 4^a and 4^b, and having respectively in circuit therewith posts 6, 6^a and 6^b receiving wires respectively 7, 7^a and 7^b. Knives 4, 4^a and 4^b respectively are insertable into clips 8, 8^a and 8^b, the said clips being in circuit respectively with wires 9, 9^a and 9^b. Posts 10 mounted on base 2 support a magnetic catch operating device 11 which comprises generally an electromagnet 11^c and a catch 11^a with suitable connections for operating said catch 11^a by said electromagnet 11^c to throw same into or out of engagement with catch 15^a. This mechanism may be of any of the ordinary devices for this purpose commonly on the market under the name of door openers, the particular form being immaterial to this invention. As here shown this mechanism comprises a toggle 11^b—11^c normally supported by a pivoted member 11^d controlled by a spring 11^e and adapted to be thrown out of supporting relation with the toggle by the operation of arm 11^e when drawn by magnets 11^c (see Figs. 4 and 5). Mounted on knives 4, 4^a and 4^b is an insulated strip 12 carrying a latch 15 having a withdrawal catch 15^a operated by an insulated knob 15^b. Insulated strip 12 has an extension member 16 extending beyond the pivots 5, 5^a and 5^b and engaging a spring 17, which spring is affixed to the base 2, and tends to throw open the switch. The switch is held against the force of spring 17 by the coacting catches 15^a and 11^a, the withdrawal of either of which will release the switch to the operation of the spring.

The wiring system comprises wires 9 and 9^b forming a circuit when the switch is closed respectively with wires 7 and 7^b and connected with such devices as it is desired to have in and out of circuit.

The central knife 4^a closes and opens a circuit at 8^a through wires 9^a and 7^a. Wire 9^a passes through a battery or other energizing means at 12 and to and through a switch 7^a it being possible to use any number of these switches and when desired on circuit with a wire 7^a. Wire also forms a circuit through coils 11^c. Thus, when switch 7^a is closed and the knife switch is also closed, batteries 12 energize coils 11^c, which releases catch 11^a and the knife switch springs open. Immediately upon the springing open of the

knife switch the circuit through wires 7^a and 9^a is broken at 8^a, thus immediately the circuit which is closed by the switch 7' is automatically broken as soon as the purposes 5 of breaking the main circuit have been accomplished, thus preventing the exhaustion of the battery should the switch 7' be left closed.

While the foregoing description is for a 10 knife switch having three blades, the same method of construction will apply to switches for different currents—whether two, three, four or five blades are used in the switch.

15 What we claim is:

1. In combination, a knife switch adapted to make and break a principal and a secondary circuit, interacting catches controlling said knife switch, one of said catches 20 being manually operated while the other is controlled magnetically through the secondary circuit, and independent means for making and breaking said secondary circuit.
2. In combination with a switch adapted 25 to make and break a principal and secondary circuit, a pair of engaging catches, magnetic means operated by said secondary current for operating one of the catches and means for opening the switch and breaking 30 both the principal and secondary currents upon the release of either of said catches.
3. In combination with a switch, a pair 35 of coating catches, magnetic means for operating one of said catches, manual means for the operation of the other of said catches, and means to open the switch operative upon the release of either of the said catches.
4. In combination, a knife switch having 40 three blades, spring means for opening said

switch, magnetic means for releasing said switch to be opened by said spring, an electrical circuit through one of said knives energizing said magnetic means, an independent electrical circuit through the other 45 two of said knives, all of said circuits broken by the opening of said switch, and auxiliary means for making or breaking the current controlling the magnetic release.

5. A means for automatically breaking a 50 circuit from a remote point, or points, comprising a switch and means for urging said switch to open, two coating catches for holding said switch in closed position, magnetic means for withdrawing one of said 55 catches, and manual means to withdraw the other catch, the withdrawal of either catch being adapted to release said switch.

6. In combination, an insulated base member, a knife switch mounted on said base member, an insulated strip mounted on said knife switch, an extension member from said insulated strip, a spring between said extension member and said base member, said spring tensioned to yieldingly hold 60 said knife switch in open relation, a manually operated catch mounted on said insulated strip, a magnetically operated catch positioned relative to said manually operated catch to engage the same so that the 65 release of either one of said catches releases said switch to be opened by said spring, and means for electrically energizing said magnetically operated catch independently of the main current.

In testimony whereof we affix our signatures.

NORRIS E. NELSON.
OTTO NELSON.
